[57] CLAIM

The ornamental design for a mounting base for clocks
or the like, as shown and described.

DESCRIPTION

FIG. 1 is a top plan view of a mounting base for clocks
or the like showing my new design;

FIG. 2 is a right side elevational view, the left side
elevational view being a mirror image;

FIG. 3 is a front elevational view, the rear elevational
view being a mirror image; and

FIG. 4 is a bottom plan view.

FIG. 1

FIG. 2

FIG. 3

FIG. 4
